UNITED STATES PATENT OFFICE.

DANA S. TEWKSBURY AND ALBERT E. NEWTON, OF KANKAKEE, ILLINOIS.

FURNACE-DOOR MOUNTING.

Application filed June 5, 1924. Serial No. 718,049.

Our invention relates to fuel doors for furnaces, and more particularly to doors of this character that are slidably mounted.

The invention has for one of its objects 5 the provision of novel means for mounting a door of the character stated that will permit the door to be easily and quickly raised into opened position and that will when the door is released, and during its downward 10 movement into closed position move it into air tight contact with its casing.

A further object of the invention is the provision of novel and simple means through the medium of which the door may be 15 readily raised into opened position and which will when released permit the door to rapidly gravitate into closed position.

With the above and other objects in view, the invention consists in the construction, 20 combination and arrangement of parts hereinafter fully described and claimed, and illustrated in the accompanying drawing, wherein:

Figure 1 is a view in front elevation of 25 a furnace illustrating the application of the door mounting and operating means,

Figure 2 is a sectional view taken on the horizontal plane indicated by the line 2—2 30 of Figure 1, and

Figure 3 is a detail sectional view taken on the vertical plane indicated by the line 3—3 of Figure 1.

Referring to the drawing by reference numerals, 1 designates the fuel door, 2 the 35 fuel door casing, 3 the ash pit door, and 4 the body of a furnace which may be of any well known construction.

In accordance with our invention, the door 1 is slidably mounted upon the casing 40 2 through the medium of vertical flanges 5 at the lateral sides of the casing and vertical channel bars 6 at the lateral edges of 45 the door. The opposing sides 7 and 8 of the flanges 5 and bars 6, respectively, are downwardly and inwardly inclined to cause the door 1 to move inwardly during its downward or closing movement, whereby to establish an air tight connection between the door and the casing 2 when the former is in 50 a fully closed position. The downward or closing movement of the door 1, is limited by pins 9 which are positioned for contact by the lower edge of the door when the latter is in its fully closed position. While the 55 downwardly and inwardly inclined opposing sides 7 and 8 of the flanges 5 and bars

6, respectively, establish an air tight connection between the door 1 and the casing 2 when the former is in fully closed position, they will not noticeably interfere with the elevation of the door into opened position inasmuch as the initial upward movement of the door results in a loose connection being established between the flanges 5 and bars 6.

A lever 10 which is mounted upon a pivot 11 for movement in a plane parallel with the front side of the door 1, provides means by which the door may be raised into opened position. The pivot 11 is carried by a 70 bracket 12 which is secured to the furnace at one side of the door 1 and at a point between the upper and lower edges of the door. The lever 10 extends inwardly and outwardly beyond the pivot 11. The inner portion of the lever 10 curves downwardly and is provided at its lower end with an angular extension 13 which is of arcuate formation in cross section and the upper 75 convex edge of which contacts with a wear piece 14 secured to the lower edge of the door 1. If desired, this part 14 may be made separately and secured to the door, or the lower edge of the door may be enlarged 80 to provide the same. The outer portion of the lever 10 inclines upwardly and is provided with a plurality of openings 15 through one of which passes the angular upper end 16 of a vertically disposed rod 17. A nut 16^a is mounted upon the angular 85 end 16 of the rod 17 to prevent the rod from becoming accidentally disconnected from the lever 10. The lower end of the rod 17 is pivotally connected as at 18 to a pedal lever 19 which in turn is pivoted as at 20 to a 90 bracket 21 secured to the furnace. As the lever 10 is provided with more than one of the openings 15, the rod 17 may be connected to the lever at the desired or required 95 distance from the pivot 11.

A downward pressure applied to the pedal lever 19 will rock the lever 10 upon its pivot 11 in a direction to swing its inner end upwardly, and this movement of the lever 10 will raise the door 1 into opened position, as indicated in dotted lines in Figure 1. When the lever 19 is released, the door 1 will gravitate into closed position, and this movement of the door will return the lever 10 to its normally depressed position and the 105 lever will return the lever 19 to its normally raised position. As the angular end 110

13 of the lever 10 has a sliding contact with the wear plate 14 on the lower edge of the door 1, there will be no binding action between these parts during the raising and lowering of the door, with the result that the door may be easily and quickly opened and will rapidly return to closed position when released.

From the foregoing description, taken in connection with the accompanying drawing, it should be apparent that we have provided simple and efficient means for establishing an air tight connection between the furnace door and its casing when the former is in fully closed position, and that we have provided simple and efficient means through the medium of which the door may be easily and quickly opened by one foot leaving both hands free to feed coal to the furnace.

It should be understood that the drawing is merely illustrative and does not pretend to give exact proportions. Furthermore, the said drawing is illustrative of a preferred

construction, it being my expectation that various changes and modifications may be made without departing from the spirit and scope of the invention.

What is claimed is:—

Means for slidably mounting a furnace door on its casing for upward movement to uncover the opening in the casing and downward movement to cover the opening, comprising vertical flanges on the casing, vertical channel bars on the door and embracing the flanges, the inner opposing sides of the flanges and channel bars being downwardly and inwardly inclined to carry the door bodily in the direction of the casing during its downward movement, and stops carried by the casing below the opening therein and upon which the door rests when in position to fully close the opening.

In testimony whereof we affix our signatures.

DANA S. TEWKSBURY.
ALBERT E. NEWTON.
